Application January 29, 1948, Serial No. 5,064

8 Claims. (Cl. 318—31)

1

This invention relates to electric control apparatus to control an electric motor for placing a load in any desired position and stopping the load motor when the load is placed in the selected position.

In control apparatus of the general type above referred to, the control means are usually united in a transmitter located at a control point, while the load and the load motor are united in a receiver located at a remote point. The transmitter and the receiver are frequently separated by a considerable distance. As a result, the required signal transmitting means between the transmitter and the receiver are rather expensive and difficult to keep in good repair.

One of the objects of the invention is to provide a novel and improved control apparatus in which the transmitter and receiver are connected by no more than two electric signal transmitting means, thereby substantially reducing the number of transmitting means, as hitherto required for control apparatus of the general type above referred to.

Another object of the invention is to provide a novel combination of a control apparatus of the general type above referred to with means to transmit signals received at the remote point to the control point and to energize these means through electric transmitting means that are employed to connect the transmitter with the receiver.

Another object of the invention is to provide a novel and improved apparatus of the general type above referred to, including a back indicator which is energized through the electric transmitting means that serve to connect the transmitter and the receiver, thereby attaining a further reduction of the electric transmitting means required for operation of the control apparatus.

The term "electric signal transmitting means" as herein sometimes used is intended to refer to and to include both physical connections, such as wires or conductors, and wireless connections such as radio channels.

Other and further objects, features and advantages of the invention will be pointed out in the subsequent description and in the appended claims forming part of the application.

This application is a continuation in part of our copending application Ser. No. 711,110 filed Nov. 20, 1946, now abandoned.

On the accompanying drawings several now preferred embodiments of a control apparatus according to the invention are shown by way of illustration and not by way of limitation.

2

In the drawings:

Fig. 1 is a control apparatus according to the invention including a transmitter employing independently movable control members, and

5 Fig. 2 is a modification of the control apparatus including a transmitter producing current impulses as control signals.

Referring now to Fig. 1 of the drawings more in detail, the control apparatus consists of a 10 transmitter generally designated T and a receiver generally designated R. The transmitter, located at a control point, serves to control the position of a load located at a remote point. There are also provided a back-indicator to indicate the position of the load at the control point and means to transmit signals received at the receiver to the transmitter.

More in detail, the transmitter includes a control unit, generally designated 10. This control 20 unit comprises two electrically conductive segments 11 and 12 supported on a rotatably mounted insulation disc 13 and separated by a gap 14. Segment 11 is electrically connected to a slip ring 15 and segment 12 to a slip ring 16, both 25 slip rings being also supported on insulation disc 13. The disc is connected by gears 17 and 18 and transmission means 19 to a pilot motor 20. Segments 11 and 12 are slidably engaged by a contact element 21 of a rotatable contact arm 22 mounted co-axially with disk 13. Contact element 21 is so designed that it can either bridge gap 14 (as shown on the drawings) or is disengaged from both contact segments when occupying gap 14. A knob 23 serves to rotate contact 30 arm 22, either directly or through a reduction gear. The contact arm is connected by a lead 25 to one terminal of an A. C. or D. C. source of current 26. Slip ring 15 is connected by a lead 27 to the outer terminal of a field winding 28, and slip ring 16 is connected by a lead 29 to the outer terminal of a second field winding 30. The inner terminals of the field windings are joined by a lead 31 which is connected by a lead 32 to one terminal of the armature 33 of pilot 35 motor 20, the other terminal of the motor armature being connected by a lead 34 to the second terminal of source of current 26. The two field windings serve to reverse the direction of motor rotation and may also be employed to brake the motor electro-dynamically. Lead 27 is connected by a lead 35 to one coil terminal of a relay 36 and lead 29 is connected by a lead 37 to one coil terminal of a second relay 38. The other coil terminals of the relays are joined by a lead 39 which

40 45 50 55 55 in turn is connected by a lead 40 to supply lead

34. Relay 36 controls an armature 41 which engages a contact 42 when the relay is energized and a contact 43 when the relay is de-energized. Similarly, relay 38 controls an armature 44 which engages a contact 45 when the relay is energized and a contact 46 when the relay is deenergized. Contacts 42 and 45 are connected by leads 47 and 48 respectively to a terminal 120 of an oscillator 50 of conventional design connected by leads 49, 49' to source of current 26 or a separate source of current. Contacts 43 and 46 are connected by leads 51 and 52 respectively to another terminal 121 of the oscillator. Leads 51 and 52 include capacitors 53 and 54 respectively, serving as tuning capacitors of the oscillator. Oscillator 50 is so constructed that it is capable of producing several different frequencies, for instance frequencies f_1 or f_2 , depending on whether capacitor 53 or 54 is connected across the terminals 120 or 121. The output side of the oscillator is connected by leads 55 and 56 respectively with two leads 57 and 58 which serve to connect the transmitter of the control apparatus with the receiver. Leads 57 and 58 are connected by leads 59 and 60 respectively to a selective amplifier 61 of conventional design which is tuned to frequency f_1 and by leads 62 and 63 respectively to a second selective amplifier 64 of conventional design, tuned to the frequency f_2 . The amplifiers are connected by leads 8 and 8' to a source of current 76. Amplifier 61 is connected by leads 65 and 66 respectively to the coil terminals of a relay 67, and similarly, amplifier 64 is connected by leads 68 and 69 respectively to the coil terminals of a relay 70. Relay 67 controls an armature 71 which engages a contact 72 when amplifier 61 is energized. Similarly relay 70 controls an armature 73 which engages a contact 74 when amplifier 64 is energized. Armatures 71 and 73 are connected by a lead 75 to one terminal of source of current 76 or a separate source of current. Contacts 72 and 74 are connected by leads 77 and 78 respectively to the outer terminals of reversing field windings 79 and 80 respectively of a load motor, generally designated 81. The inner terminals of the field windings are joined and connected by a lead 82 to one terminal of motor armature 83 of the load motor, the other terminal of the motor armature being connected by a lead 84 to the second terminal of source of current 76. Motor 81 moves a load 85 by means of suitable transmission means 86 which may include gearing 87. Load 85 may consist of any suitable device or element and include a pointer 88 coacting with a calibrated scale (not shown).

Pilot motor 20 may be a small motor just sufficient to operate control unit 10, whereas load motor 81 may be a powerful motor suitable to move a heavy load. Various types of motors can be employed as pilot motor and load motor respectively, including motors which will operate at different speed, such as non-synchronous motors. As a result, the control unit of the transmitter permits control of the operation of the load motor, as will be more fully described hereinafter, but the position of the pilot motor and hence of contact arm 22 may or may not be proportional to the position of the load. Consequently, indicating means are required to back-indicate the position of the load to the control point.

As previously mentioned, one of the objects of the invention is a novel and improved back-indicating means which makes use of the two leads 57 and 58 connecting the transmitter with the receiver.

According to a further object of the invention, the same leads 57 and 58 are employed to transmit signals, audible or non-audible, from the remote point to the control point.

For these purposes, lead 57, at the remote point, is connected by a lead 90 to the wiper 92 of a potentiometer 93 which in turn is connected by leads 94 and 95, respectively, to a D. C. source of current 96. Lead 90 is further connected by a lead 97 through a capacitor 98 and leads 99, 34 to the minus terminal of the source of currents 96, and by a lead 100 to one terminal of the secondary 101 of a transformer, generally designated 102. Lead 58 is connected by a lead 103 and low pass filter 91 to the other terminal of secondary 101. The primary 104 of the transformer is connected to receive A. C. signals, produced for instance by the output of a radio receiver 89.

Wiper arm 92 of the potentiometer is operatively connected by suitable transmission means 105 to load 85 so that the position of the wiper arm of potentiometer 93 is always indicative of the load position.

At the control point, lead 57 is connected by a lead 106 and a low pass filter 107 to one terminal of a D. C. measuring instrument 108. This instrument has a pointer 109 coacting with a scale 110 calibrated to indicate the positions of lead 85, as will be more fully explained hereinafter. The other terminal of meter 108 is connected by a lead 111 to one terminal of the primary 112, of a transformer generally designated 113, the other terminal of primary 112 being connected by a lead 114 through low pass filter 107 to lead 58. A capacitor 115 is connected by a lead 116 to the terminals of meter 108. The A. C. impedance of this capacitor is so selected that it is small in comparison with the A. C. impedance of meter 108 so that the capacitor will operate as a bypass, allowing A. C. to flow through the capacitor, whereas D. C. will flow through the meter. The secondary 117 of transformer 113 is connected to an audio amplifier 118 which serves to reproduce at the control point signals received by transformer 102 at the remote point.

Low pass filter 91 is so designed that it will pass signals received by transformer 102 but will block signals having a frequency f_1 or f_2 , thereby eliminating any influence of signals having such frequency upon the operation of amplifiers 61 and 64. Similarly low pass filter 107 is so designed that it will prevent signals having a frequency f_1 or f_2 and produced by oscillator 50 to reach audio amplifier 118.

The operation of the control apparatus according to Fig. 1 is as follows:

When contact element 21 engages segments 11 and 12, energizing circuits are closed for both field windings 28 and 30. The circuit of winding 28 may be traced as follows: from one terminal of source of current 26 by lead 25, contact arm 22, contact element 21, segment 11, slip ring 15, lead 27, winding 28, leads 31 and 32, armature 33 and lead 34 back to the other terminal of source of current 26. The circuit for winding 30 can be similarly traced through segment 12. As a result, both field windings are energized in opposition, thereby braking motor 20 electro-dynamically. In addition, energizing circuits are closed for both relays 36 and 38. The circuit of relay 36 may be traced from lead 27 by lead 35, coil 36, leads 39 and 40 back to lead 34. The circuit of relay 38 may be similarly traced. Consequently, both relays will attract their respec-

tive armatures 41 and 44, so that oscillator 50 remains inoperative.

As will be evident from the previous explanation, a similar result can be obtained by arranging contact element 21 and gap 14 in such a manner that contact element 21 is disconnected from both segments when the gap is in alignment with the contact element. With such arrangements, motor 20 and both relays 36 and 38 will be disconnected. It should further be noted in this connection that it is quite practical and well-known in the art to interpose a relay system between motor 20 and the segments which relay system is controlled by the relative position of segments 11 and 12 and contact element 22 and in turn controls the operation of pilot motor 20.

Let it now be assumed that it is desired to displace load 85 in counter-clockwise direction. For this purpose contact arm is turned towards the left by means of knob 23, thereby placing contact element 21 in engagement with segment 11 only. As a result, field winding 30 is deenergized while field winding 28 remains energized through the circuit as previously traced. Consequently, pilot motor 20 rotates disk 13 in a direction selected to cause gap 14 to follow the displaced contact arm 22.

The displacement of the contact arm further causes relay 38 to be de-energized so that this relay releases its armature 44 which now engages contact 46, thereby closing a capacitance circuit for oscillator 50 which may be traced as follows: from oscillator 50 by lead 47, contact 42, armature 41, armature 44, contact 46, lead 52 tuning capacitor 54 and lead 51 back to oscillator 50. The oscillator is now energized to oscillate frequency f_1 or f_2 , say frequency f_1 , which is transmitted by leads 51, 58 and leads 59, 60 to selective amplifier 61 which in turn energizes contact 72, thereby closing a circuit for load motor 81 which may be traced as follows: from one terminal of source of current 76 by lead 75, armature 71, contact 72, lead 71, field winding 79, lead 82, motor armature 83 and lead 84 back to the other terminal of the source of current 76. As a result, motor 81 is energized to rotate in a direction as determined by the displacement of contact arm 22.

When now gap 14 catches up with contact arm 22 and is again bridged by contact element 21, pilot motor 20 is stopped by the energization of both field windings 28 and 30, as previously explained, and load motor 81 is also stopped, as now both relays 36 and 38 are again energized, thereby disconnecting the tuning circuit of oscillator 50.

It will be evident that the operation of the control apparatus is similar when contact arm 22 is placed in engagement with contact segment 12. In this case, oscillator 50 is energized to produce frequency f_2 , and pilot motor 20 and load motor 81 are connected to rotate in the opposite direction.

Load motor 81, when operative, rotates pointer 88 of load 85 correspondingly so that the position of load 85 and pointer 88 will be controlled by the displacement of contact arm 22. However, the position of the load and the pointer do not necessarily correspond to the angular displacement of contact arm 22, as pilot motor 20 and load motor 81 may rotate at different speeds or different ratios of transmission may be provided between the motors and the parts rotated thereby. Consequently, as previously mentioned, back-indicating means must be provided, the op-

eration of which will now be described. As will be apparent from the drawing, the location of the load causes wiper arm 92 of potentiometer 93 to be rotated correspondingly. As a result, the direct current energizing D. C. meter 108 will be varied accordingly. The energizing circuit of the meter may be traced as follows: from wiper arm 92 by lead 90, low pass filter 91, leads 90, 57, low pass filter 107, meter 108, lead 111, primary 112, lead 114, low pass filter 101, leads 58, 103, low pass filter 91, secondary 101, leads 99, 94 and resistance 93. As a result, pointer 109 of meter 108 will always indicate the position of the load at the remote point.

Let it now be assumed that signals received by the primary 104 of transformer 102 shall be transmitted to audio amplifier 118. It will be apparent that these signals will be transmitted from the remote point by secondary 101, lead 90 including capacitor 98, lead 103, low pass filter 91, leads 57, 58, low pass filter 107, lead 116 including capacitor 115, leads 111 and 114, primary 112 of transformer 113, secondary 117 to the audio amplifier 118. In other words, signals received at the remote point can be made audible at the control point by using the same wire connections as are employed to control the receiver by means of the transmitter. It will further be apparent that the two wire connections between transmitter and receiver can be employed to carry other or additional signals.

The modification according to Fig. 2 is distinguished from the control apparatus according to Fig. 1 in that the frequency output of oscillator 50 is controlled by impulse producing means rather than by a control unit comprising relatively movable control members. The control of the load at the remote point by different frequencies and the arrangement of the receiver proper and of the back indicating means are the same as in Fig. 1. The same reference characters are used in both figures to designate similar or corresponding components.

It will also be evident that the arrangement of Fig. 2 lends itself to the use of radio channels instead of wire connections without departing from the spirit and scope of the invention.

Referring now to Fig. 2 in detail, the control apparatus according to this figure comprises a ratchet wheel 130 which can be rotated by means of a rotatable knob 131. A transmission 132 between wheel and knob is indicated by a dotted line. Wheel 130, when rotated, rocks a flexible contact arm 134 vibrating about a point 135 between two stationary contacts 136 and 137. A spring 138 biases arm 134 against contact 136 connected by lead 25 to source of D. C. current 26. Contact 137 is connected by a lead 139, a capacitor 140 and a resistor 141 to arm 134. Contact 137 is further connected by a lead 142 to one terminal of the coil of a relay 143, the other terminal of the relay coil being connected by a lead 144 to supply lead 34. There are further provided a variable resistor 145 and a capacitor 146 connected by leads 147 and 148 respectively in parallel to the relay coil. Armature 150 of relay 143 controls a relay contact 151 connected to oscillator lead 120. Armature 150 is disengaged from contact 151 when the relay is de-energized and is connected by a lead 152 to a contact spring 153. This contact spring coacts with two contact springs 154 and 155 both connected by leads 156 and 157 to the second oscillator connection 121. Leads 156 and 157 include capacitors 53 and 54 for control of the oscillator fre-

quencies as previously explained. Contact spring 153 is biased to be normally disengaged from either contact spring 154 and 155. For the purpose of flexing spring 153 into engagement with either one of springs 154 and 155, spring 153 is operatively connected through a friction clutch 158 of conventional design to transmission 132. As a result, rotation of knob 131 will cause spring 153 to engage either one of the springs 154 or 155 depending upon the direction of rotation. The contact springs will remain in engagement as long as knob 131 and wheel 130 respectively are rotated, the slipping of clutch 158 permitting continued rotation of the knob and the wheel. Stops 159 and 160 may be provided to limit the movements of the contact springs. When the rotation of the knob and the wheel are discontinued, spring contact 153 will return into its disengaged position due to its springiness.

The operation of the control apparatus according to Fig. 2 is as follows:

Let it be assumed that knob 131 is rotated and that the nose of arm 134 comes to rest between two teeth of wheel 130 so that arm 134 engages contact 136. Let it be further assumed that the knob is rotated in such direction that contact spring 153 engages spring 154. As will be apparent, an energizing circuit is closed for relay 143 during the charging period of capacitor 140 which circuit may be traced through lead 25, contact 136, arm 134, resistor 141, capacitor 140, lead 142, the relay coil, lead 144 and lead 34 back to the source of current. Consequently, relay 143 closes contact 151 during the charging of capacitor 140, thereby connecting capacitor 53 to the oscillator through lead 120, contact 151, armature 150, lead 152, spring 153, spring 154, leads 155 and 121. As a result, oscillator 53 will produce the frequency associated with capacitor 53 which frequency in turn will control the selective means of the receiver as previously explained in detail in connection with Fig. 1. The charging current of capacitor 140 also causes charging of capacitor 146. The energizing current through the relay will cease when capacitor 146 is discharged.

As the rotation of wheel 130 is continued, the next tooth of the wheel will force arm 134 into a position engaging contact 137. Capacitor 140 is now discharged through resistor 141, arm 134 and lead 139 so that the apparatus is ready for a new impulse re-energizing relay 143 when contact 133 is re-engaged by arm 134.

As will be evident, the length of the impulses is controlled by the capacitance of capacitor 146 and also by the adjustment of resistor 145 or other components of the network. Any desired length of impulses can be attained by adjusting the resistor accordingly and it is also quite practical to adjust the resistor in such manner that at a certain rate of rotation of knob 131 or wheel 130 relay 143 remains energized between impulses.

As will be apparent from the previous description, rotation of knob 131 permits faster or slower step by step movement of load 85 until the same is placed in the selected position which is back indicated as described in connection with Fig. 1.

While the invention has been described in detail with respect to certain now preferred examples it will be understood by those skilled in the art after understanding the invention that various changes and modifications may be made without departing from the spirit and scope of the invention, and it is intended therefore in the

appended claims, to cover all such changes and modifications.

What is claimed as new and desired to be secured by Letters Patent is:

1. An electric control apparatus of the follow-up type for placing a useful load in any desired position comprising a pair of independently movable control members at a control point, drive means including a reversible pilot motor for moving one of the members, the other being otherwise movable, circuit means including the control members and the pilot motor for controlling the rotational direction thereof by the relative position of the control members, a reversible motor for moving the load at a remote point, oscillating means at the control point capable of producing a plurality of different frequencies, second circuit means including the control members and the oscillating means for frequency control of the latter by the relative position of the control members, a plurality of selective means at the remote point, each responsive to a different one of the frequencies of the oscillating means, electric connections between the oscillating means and the selective means for control of the latter by the oscillating means, and third circuit means including the selective means and the load motor for controlling the rotational direction and the stopping thereof by the selective means, said pilot motor and said oscillating means being connected to be rendered inoperative for the purposes aforesaid when said control members reach a predetermined position relative to each other.

2. An electric control apparatus of the follow-up type for placing a load in any desired position comprising a pair of independently movable control members at a control point, one member including electrically conductive elements separated by a gap, the other member including a contact element for engaging the conductive elements, drive means including a reversible pilot motor for moving one of the members, the other being otherwise movable, circuit means including the movable member and the pilot motor for controlling the rotational direction of the latter by the relative position of the control members, a reversible motor for moving the load at a remote point, oscillating means at the control point capable of producing two different frequencies, second circuit means including the control members and the oscillating means for energizing the latter with one or the other frequency corresponding to the relative position of the control members, a pair of selective means at the remote point, one of the selective means being responsive to one of said frequencies and the second being responsive to the other frequency, electric connections between the oscillating means and the selective means for energizing one of the selective means as controlled by the frequency of the oscillating means, and third circuit means including the selective means and the load motor for controlling the rotational direction and the stopping thereof by the energized selective means, said pilot motor and said oscillating means being connected to be rendered inoperative for the purpose aforesaid when the contact element occupies the gap.

3. An electric control apparatus of the follow-up type for placing a useful load in any desired position comprising a pair of independently movable control members at a control point, one member including electrically conductive elements separated by a gap, the other element in-

cluding a contact element for engaging the conductive elements, drive means including a reversible pilot motor for moving one of the members, the other being otherwise movable, circuit means including the control members and the pilot motor for controlling the rotational direction of the latter by the relative position of the control members, a reversible motor for moving the load at a remote point, oscillating means at the control point capable of producing a plurality of different frequencies, relay means including a pair of coils connected in circuits with respective ones of the conductive elements for energizing one or the other coil as controlled by the relative position of the control members, said relay means connected in circuits with the oscillating means for frequency control of the latter by the relative position of the control members, a plurality of selective means at the remote point, each responsive to a different one of the frequencies of the oscillating means, electric connections between the oscillating means and the selective means for energizing the selective means responsive to a particular frequency produced by the oscillating means, and second relay means including a pair of coils connected with respective ones of the selective means for energizing one or the other of said relay coils corresponding to the energization of the respective selective means, said second relay means electrically connected with the load motor for controlling the rotational direction and the stopping of the latter by the second relay means, said pilot motor and said oscillating means being connected to be rendered inoperative for the purposes aforesaid when the contact element occupies the gap.

4. An electric control apparatus of the follow-up type for placing a useful load in any desired position comprising a pair of independently movable control members at a control point, one member including electrically conductive elements separated by a gap, the other element including a contact element for engaging the conductive elements, drive means including a reversible pilot motor for moving one of the members, the other being otherwise movable, circuit means including the control members and the pilot motor for controlling the rotational direction thereof by the relative position of the control members, a reversible motor for moving the load at a remote point, oscillating means at the control point capable of producing a plurality of different frequencies, second circuit means including the control members and the oscillating means for frequency control of the latter by the relative position of the control members, a plurality of selective means at the remote point, each responsive to a different one of the frequencies of the oscillating means, electric connections between the oscillating means and the selective means for control of the latter by the oscillating means, third circuit means including the selective means and the load motor for controlling the rotational direction and the stopping thereof by the selective means, said pilot motor and said oscillating means being connected to be rendered inoperative for the purpose aforesaid when the said contact element occupies the gap, electric indicating means at the control point, a source of current included in a circuit with the indicating means through said electric connections, and means for varying the amount of energy supplied to the indicating means corresponding to the position of the load for back indicating the load position.

5. An electric control apparatus of the follow-

up type for placing a useful load in any desired position comprising a pair of independently movable control members at a control point, one member including electrically conductive elements separated by a gap, the other element including a contact element for engaging the conductive elements, drive means including a reversible pilot motor for moving one of the members, the other being otherwise movable, circuit means including the control members and the pilot motor for controlling the rotational direction thereof by the relative position of the control members, a reversible motor for moving the load at a remote point, oscillating means at the control point capable of producing a plurality of different frequencies, second circuit means including the control members and the oscillating means for frequency control of the latter by the relative position of the control members, a plurality of selective means at the remote point, each responsive to a different one of the frequencies of the oscillating means, electric connections between the oscillating means and the selective means for control of the latter by the oscillating means, third circuit means including the selective means and the load motor for controlling the rotational direction of the load motor and the stopping thereof by the selective means, said pilot motor and said oscillating means being connected to be rendered inoperative for the purposes aforesaid when the said contact element occupies the gap, electric indicating means at the control point connected with said electric connections, an independent source of current at the remote point connected with said electric connections, and electric means mechanically controlled by the load position for varying the amount of energy supplied to the indicating means from said source of current through said electric connections corresponding to the angular position of the load, thereby back indicating the load position.

6. An electric control apparatus of the follow-up type for placing a useful load in any desired position comprising a pair of independently movable control members at a control point, one member including electrically conductive elements separated by a gap, the other element including a contact element for engaging the conductive elements, drive means including a reversible pilot motor for moving one of the members, the other being otherwise movable, circuit means including the control members and the pilot motor for controlling the rotational direction thereof by the relative position of the control members, a reversible motor for moving the load at a remote point, oscillating means at the control point capable of producing a plurality of different frequencies, second circuit means including the control members and the oscillating means for frequency control of the latter by the relative position of the control members, a plurality of selective means at the remote point, each responsive to a different one of the frequencies of the oscillating means, electric connections between the oscillating means and the selective means for control of the latter by the oscillating means, third circuit means including the selective means and the load motor for controlling the rotational direction of the load motor and the stopping thereof by the selective means, said pilot motor and said oscillating means being connected to be rendered inoperative for the purposes aforesaid when the said contact element occupies the gap, electric indicating means at the control point connected with said electric connections, an inde-

pendent source of current at the remote point connected with said electric connections, a potentiometer included in a circuit with the independent source of current, and transmission means operatively connecting the movable contact of said potentiometer with the load for varying the amount of energy supplied to the indicating means through said electric connections corresponding to the angular position of the load, thereby back indicating the load position.

7. An electric control apparatus of the follow-up type for placing a useful load in any desired position comprising a pair of independently movable control members at a control point, one member including electrically conductive elements separated by a gap, the other element including a contact element for engaging the conductive elements, drive means including a reversible pilot motor for moving one of the members, the other being otherwise movable, circuit means including the control members and the pilot motor for controlling the rotational direction thereof by the relative position of the control members, a reversible motor for moving the load at a remote point, oscillating means at the control point capable of producing a plurality of different frequencies, second circuit means including the control members and the oscillating means for frequency control of the latter by the relative position of the control members, a plurality of selective means at the remote point, each responsive to a different one of the frequencies of the oscillating means, electric connections between the oscillating means and the selective means for control of the latter by the oscillating means, third circuit means including the selective means and the load motor for controlling the rotational direction of the load motor and the stopping thereof by the selective means, said pilot motor and said oscillating means being connected to be rendered inoperative for the purposes aforesaid when the said contact element occupies the gap, electric means capable of receiving signals connected at the remote point with said electric connections for transmitting the said signals to the control point, and electric signal means responsive to said signals connected at the control point with said electric connections.

8. An electric control apparatus of the follow-up type for placing a useful load in any desired position comprising a pair of independently movable control members at a control point, one member including electrically conductive elements separated by a gap, the other element including a contact element for engaging the conductive elements, drive means including a reversible pilot motor for moving one of the members, the other being otherwise movable, circuit

means including the control members and the pilot motor for controlling the rotational direction thereof by the relative position of the control members, a reversible motor for moving the load at a remote point, oscillating means at the control point capable of producing a plurality of different frequencies, second circuit means including the control members and the oscillating means for frequency control of the latter by the relative position of the control members, a plurality of selective means at the remote point, each responsive to a different one of the frequencies of the oscillating means, electric connections between the oscillating means and the selective means for control of the latter by the oscillating means, third circuit means including the selective means and the load motor for controlling the rotational direction of the load motor and the stopping thereof by the selective means, said pilot motor and said oscillating means being connected to be rendered inoperative for the purposes aforesaid when the said contact element occupies the gap, electric means capable of receiving signals connected at the remote point with said electric connections for transmitting the said signals to the control point, electric signal means responsive to the signals connected at the control point with said electric connections, filter means included in said electric connections, said filter means being constructed to block signal frequencies corresponding substantially to one of the frequencies of the oscillating means to reach the selective means, thereby preventing such frequencies to affect the selective means, and second filter means included in said electric connections, said second filter means constructed to block frequencies originating in the oscillating means to reach the signal means.
